UNITED STATES PATENT OFFICE.

FREDERICK S. OREM, OF BALTIMORE, MARYLAND.

ATTACHMENT FOR INTERNAL-COMBUSTION ENGINES.

1,215,974.

Specification of Letters Patent.

Patented Feb. 13, 1917.

Application filed March 6, 1915. Serial No. 12,583.

To all whom it may concern:

Be it known that I, FREDERICK STRATTNER OREM, a citizen of the United States, residing at Baltimore, Maryland, have invented certain new and useful Improvements in Attachments for Internal-Combustion Engines, of which the following is a specification.

My present invention relates to an improved attachment for internal combustion engines, designed as a choke or stop for all impurities in the air supply thereof.

Such engines, as used for motor vehicles and the like are constantly inspiring along with the air necessary to combine with the gasolene to form the combustible mixture, considerable quantities of fine dirt or dust and at times more or less moisture.

Much of this fine dirt or dust, coming from the surface of a Macadam road is of a very hard or gritty nature.

A portion of the dirt and dust combines with the lubricating oil and becomes deposited on the walls of the combustion chamber, spark plugs and piston heads, while a part finds its way into the cylinders where it causes rapid wear between piston rings, pistons and cylinders and finally reaches the crank case where it mixes with the lubricating oil and with this oil bathes or lubricates all the interior and moving parts, including crank and rod bearings and also gears. It is evident that this grinding which takes place between the metal and fine Macadam dirt will soon result in great wear and rapid deterioration of the motor.

In devising my present invention I have aimed to provide an extremely simple and economical device adaptable to any ordinary internal combustion engine which will effectively prevent such impurities as above referred to from reaching the interior of the engine.

The invention includes the novel features of construction and arrangement and combination of parts as defined by the appended claims, an embodiment of the invention being hereinafter described in connection with the accompanying drawings, in which;

Figure 1 is a side elevation showing a manifold intake pipe and carburetor of conventional form with my attachment applied thereto.

Fig. 2 is a plan view of the attachment, and

Fig. 3 is a section on line 3—3 of Fig. 2.

Referring by reference characters to this drawing, the numeral 1 designates the lower portion of the pipe of the intake manifold of an internal combustion engine and 2 the carburetor thereof having an upturned air intake indicated at 3.

To this air intake I secure my improved attachment which comprises an approximately dish-shaped member 4 having a depending tubular portion 4^a designed to be connected to the air intake of the carburetor in any suitable manner, as by inter-engaging threads as shown.

To the peripheral edge of this dish-shaped member I secure the medium for eliminating from the air the impurities referred to. Such medium is shown as a diaphragm 5 which must be of such nature as to be practically impervious to air when the motor is not running, but which, when the engine is in action will, under the suction thereof, permit the passage of all the air necessary to form the combustible mixture. The diaphragm may be composed of pressed material having the fibers closely associated, or it may be a closely woven textile fabric, but I have found felt to be a material well adapted for the purpose.

In order that ample air may pass through the diaphragm when the engine is running it is necessary that the diaphragm should have a much larger area than the interior cross section of the intake of the carburetor, and I have found that the relative proportions of forty to one give excellent results.

An advantageous manner of securing the diaphragm to its supporting member is to clamp it between a pair of spider members 6^a and 6^b, the edges of which may be detachably connected to the member 4 by bolts 7 and thumb nuts 7^a.

The central portion of the diaphragm is preferably further supported by a bolt 8 passing therethrough and secured thereto by washers 8^a and lock nut 8^b, the ends of the bolt being secured to the spiders by washers and lock nuts as indicated at 8^c and 8^d.

I have found by practical demonstration that an attachment such as above described so eliminates all foreign matter and impurities and moisture from the air passing to the engine that the life of the motor is greatly prolonged and trouble due to the fouling of the motor is prevented. I have found that much of the difficulty encountered in removing carbon from engine cylin-

ders is due to the presence of mineral matter drawn in with the dust, such as silicon, which cannot be removed by the oxygen burning methods, but can only be removed by taking down the engine and scraping it off.

With my attachment, such deposits of extraneous matter are absolutely prevented.

Having thus described my invention what

10 I claim is:

1. The combination with the carbureter of an internal combustion engine, of an attachment for the air intake of said carbureter comprising a sheet of dust excluding material of such relative area and porosity as to permit the passage of air under the suction produced by the engine when running without unduly affecting the gasolene supply to the carbureter, and of such density as to cause the dust to be intercepted at the outer surface and prevented from penetrating and clogging the pores, whereby said

dust is dislodged from said surface by vibration or air currents.

2. The combination with the carbureter 25 of an internal combustion engine, of an attachment for the air intake of said carbureter comprising a sheet of felt sustained by its edges and of such relative area and porosity as to permit the passage of air 30 under the suction produced by the engine when running without unduly affecting the gasolene supply to the carbureter and of such density as to cause the dust to be intercepted 35 at the outer surface and prevented from penetrating and clogging the pores, whereby said dust is dislodged from said surface by vibration or air currents.

In testimony whereof, I affix my signature in presence of two witnesses.

FREDERICK S. OREM.
